[57] CLAIM

The ornamental design for an emergency rescue signal emitter, as shown and described.

DESCRIPTION

FIG. 1 is a perspective view of an emergency rescue signal emitter showing my new design;

FIG. 2 is a front view thereof;

FIG. 3 is a top view thereof;

FIG. 4 is a right side view thereof;

FIG. 5 is a bottom view thereof;

FIG. 6 is a back view thereof;

FIG. 7 is a left side view thereof;

FIG. 8 is an enlarged sectional view taken along lines VIII—VIII in FIG. 2, the internal mechanism of the emitter being omitted; and,

FIG. 9 is an enlarged sectional view of part of the emitter indicated by the arrow A in FIG. 2 taken along lines IX—IX in the same.
